VACUUM CLEANER HOUSING

Gordon W. Goodrich, Grand Rapids, Mich., assignor to
Bissell, Inc., Grand Rapids, Mich.

Filed Aug. 5, 1974, Ser. No. 494,766

Term of patent 14 years

Int. Cl. D15—05

U.S. Cl. D7—165

Fig. 1

Fig. 2

Fig. 3

Fig. 4

Fig. 5

Fig. 6

Fig. 7

FIG. 1 is a perspective view of a vacuum cleaner housing showing my new design;

FIG. 2 is a right side elevation view thereof;

FIG. 3 is a left side elevation view thereof;

FIG. 4 is a top plan view thereof;

FIG. 5 is a front elevation view thereof;

FIG. 6 is a rear elevation view thereof; and

FIG. 7 is a bottom plan view thereof.

I claim:

The ornamental design for a vacuum cleaner housing, substantially as shown and described.
